BAG MAKING AND DISPENSING MACHINE

Gilmore T. Schjeldahl, Farmington, Minn., and Walter Von Stoesser, Lake Villa, Ill., assignors, by direct and mesne assignments, to G. T. Schjeldahl Company, Northfield, Minn., a corporation of Minnesota

Application June 8, 1955, Serial No. 513,929

5 Claims. (Cl. 154—42)

This invention relates to a bag forming and dispensing machine adapted to dispense polyethylene bags to be used at the point of filling and sealing thereof. The machine is adapted to receive a supply roll of tubularly formed or centerfolded polyethylene material either with plain or gusseted side edges. Any mention of use of tubular applies equally as well to centerfolded material. The polyethylene tubing is adapted to be fed into the bag forming machine through feed rollers.

A feature resides in regulating the bags in the machine so that any printing on the bags will be properly positioned in relation to the sealed and open end of the bag when the bag is finished and dispensed from the machine. The regulating of the bags in the machine is controlled by perforating the tubing used in making up the bag. The tubing which is adapted to be used in making up the bags on our machine is perforated at predetermined intervals and each supply roll of the tubing is formed with the perforations in properly predetermined spaced relation so that when the tubing is fed into the machine it is registered by the perforations to cut the tubing off in the desired length for the bag and at the bottom end of the same.

The machine is designed to complete the bags from a prefabricated roll of tubing and the perforations regulate the operation of the machine so that the bags are cut off and sealed automatically by means of electrically controlled sealing and cutting means and by automatically feeding the finished bag out of the machine.

It is a feature to provide a machine which is electrically operated and controlled to finish bags in any desired length from a supply roll of tubing made of polyethylene and wherein the bags may be dispensed one at a time or continuously, or the machine may be automatically operated by withdrawing a finished bag from the machine which automatically sets the machine into operation to make another bag and move the same into position to be engaged and removed from the machine. Thus, the operator may cause the machine to be operated by withdrawing a finished bag which is held in readiness to be engaged or the operator may press a button causing the machine to finish a bag from the supply roll of tubing, and if desired the machine may be set to operate continuously so long as there is a supply of tubing coming from the supply roll to make one bag after another and to automatically dispense the same.

It is also a feature to provide a roll of unperforated tubular material which may be processed through our machine in a manner to make finished bags of different predetermined lengths.

A further feature resides in providing a roll of tubular material and passing the tubular material through a printing means to print a mark on the tubular material. In this process of finishing bags, the printed mark on the material passes under an electric eye which controls the operating means of our machine to cut off the tubular material into predetermined lengths and to simultaneously seal one end thereof.

2

The features, details and objects will be more fully and clearly hereinafter defined.

In the drawings forming part of this specification:

Figure 1 is a diagrammatic side view of a machine illustrating the manner in which our invention is carried out.

Figure 2 is a roll of material used in making the bags by our method and machine.

Figure 3 illustrates the perspective of one of the finished bags.

Figure 4 diagrammatically illustrates a perforating attachment to our machine which is adapted to perforate the tubing as it is fed into the machine which perforations are spaced at predetermined intervals which in turn controls the length of bags finished by our machine.

Figure 5 diagrammatically illustrates a printing means which is adapted to print a spot or mark on the unperforated tubular material, and when the mark or spot

20 passes under an electric eye the mechanism of the machine is operated to cut off the tubing and to simultaneously operate the sealing means to seal one end of the bag.

The primary feature of this invention resides in providing a supply roll of tubular material which can be processed through a machine to form finished bags. The supply roll of tubing is prefabricated. The tubing of the supply roll may be formed with a plain side edge or with a gusseted side and the tubing is processed in a roll and is adapted to form a supply of material made of polyethylene which has been preformed into tube-like shape but wound on the roll flat so that the sides of the tubing lie against each other when the roll is complete.

The supply roll of polyethylene 10 is wound upon a core member 11 in making the roll and is adapted to be mounted upon a shaft 12 of the machine which is diagrammatically illustrated in Figure 1. The tubing 13 of the roll 10 is adapted to be unwound from the supply roll 10 as illustrated in Figures 1 and 2 and the tubing is 30 perforated with holes 14 through both walls thereof. The holes 14 in the tubing 13 are for the purpose of permitting contacting fingers to complete an electric circuit (not illustrated in the drawings) which causes the bag making machine A to operate to complete a finished bag.

45 The operation of the machine A consists in providing a pair of feed rollers 15 at the receiving end between which the tubing 13 is carried causing the tubing 13 to travel along in a horizontal direction on the bed of the machine A and between the rollers 16 to carry the tubing 13 between the discharge rollers 17.

50 Positioned between the carrying rollers 16 and the discharge rollers 17 we provide a transversely disposed cut off knife 18 and a sealing means 19 which is adapted to seal the sides of the tubing 13 transversely at 19'. The sealing 19' is adapted to be formed at the bottom of the bag B. The cut off knife or means 18 cuts the tubing 13 off along the transverse line 21 which is virtually centrally disposed in relation to the holes 14 and the cut off line 21 is directly adjacent the sealing line 19'.

55 We provide electric contact fingers or elements 20 which are adjustably positioned to be moved along the line of travel through the machine A. Thus the fingers 20 may be set in the desired position so as to cause the machine A to operate to make bags of different lengths.

60 When the fingers 20 are set in a predetermined position the bags made by the tubing 13 passing through the machine A will be of predetermined length.

65 The contact fingers 20 are adapted to engage through the holes 14 formed in spaced apart relation in the tubing 13 and electrically operated means is provided to operate the rollers 15, 16 and 17 in unison to feed the tubing 13 through the machine A. When the machine

A is set to make a predetermined length bag as the tubing 13 is passed under the electric contact fingers 20 an electric circuit (not shown) will be closed to operate the cutter 18 to cut off the tubing 13, and the heat sealing bar 19 forms the seal 19'.

The tubing 13 normally opens the electric circuit controlled by the fingers 20 as the tubing 13 passes under the fingers excepting when the fingers come in contact with the holes 14. Thus, the machine A is only operated to cut off and seal the tubing when the fingers 20 close the electric circuit for operating the cutter 18 and the sealing bar 19.

The machine A is designed to position a finished bag B with the open end 22 projecting beyond the roller 17 so that the end 22 may be engaged and the bag B withdrawn from between the rollers 17. We provide an electrically operated solenoid 23 having a core member 24 which carries a plate 25 which normally bears against the bottom of the tubing of the bag B as illustrated in Figure 1. The core member 24 of the solenoid 23 is urged by the spring 26 to cause the plate 25 to engage the under surface of the bag B. When the end 22 of the finished bag B is engaged and the bag is pulled from the machine A, the core member 24 of the solenoid 23 will be urged by the spring 26 into momentary contact with the upper plate 27 which closes an electric circuit (not illustrated in the drawings) causing the rollers 15, 16 and 17 to operate to carry the tubing 13 along in the machine A and between the plates 25 and 27. After the tubular material 13 is started through the machine, the contact fingers 20 take over causing the tubing to be cut off in the desired length and sealed by the sealing means to form the bottom of the bag B. The plates 25 and 27 are normally spaced apart to permit the tubing 13 to pass between the same. As the tubing 13 passes under the fingers 20 a circuit is closed to operate the cutting knife 18 and the sealing bar 19, another bag is completed by cutting off from the tubing 13 and sealed along the transverse line 19' at the bottom. Virtually at the same time that the electric contact plates 25 and 27 engage to close a circuit to operate the feed rollers 15, 16 and 17, the solenoid 23 will operate to open the space between the plates 25 and 27 to permit the tubing 13 to be fed between the same so that the end 22 of the bag is moved into engageable position to permit the operator to engage the bag B when desired to withdraw the same.

Normally while a bag B is in position ready to be removed from the machine A the electric contact plates 25 and 27 are held apart by the walls of the bag B or tubing 13, and the machine A will not operate at this time to draw a supply of tubing 13 from the supply roll 10. However, the moment the operator desires a bag B, he engages the end 22 and pulls the same from the machine A. This act closes a circuit through the plates 25 and 27 to cause the machine A to operate and feed sufficient tubing 13 into position to be cut off by the knife 18 and sealed by the bar 19 thereby positioning a new complete bag in readiness for use. In Figure 3 we have illustrated a completed bag B showing the side edges of the bag made with a gusset formation 28. It will also be apparent that one-half of the hole 14 will be positioned along the bottom edge 21 while the other half of one of the holes 14 will appear in the engagable end 22.

As a matter of convenience in describing the operation of the machine A, we have illustrated round holes 14. These holes are formed in the tubing after it is made from flat polyethylene film into a seamed tube. The tubing 13 is rolled with the sides of the same flattened to form a supply roll 10, and these rolls can be of any desired size. The free end of the roll is removably sealed to the outer surface of the roll 10. When a supply roll 10 is desired to be placed in the machine A, it is adapted to be mounted upon the shaft 12 and

placed in the machine with the friction belt 29 draped over the roll, and the weight 30 hinging freely at the free end of the belt 29 to provide a simple means of applying friction to the outer surface of the supply roll 10 which is adapted to keep the roll from unwinding too freely.

The machine A is illustrated in the drawings diagrammatically, and it is obvious that the same may be made in a suitable manner to carry out the operation of making individual bags as heretofore set forth. The machine may be operated as heretofore described to make one bag at a time and to stop operating as soon as the bag has been made and placed in readiness to be removed with the free end thereof projecting at the discharge end. 10 However, it will be apparent that by suitable means (not shown) the machine A may be equipped to operate automatically to make one bag after another and to discharge the finished bags on a receiving tray 31 which is also diagrammatically illustrated.

Further, the machine A may be operated by an electric push button (not illustrated) which the user of the machine operates whenever he desires the machine to be set into motion and to make a bag B.

It will also be apparent that a gang of machines A 25 may be positioned side by side or in any adjacent relation to each other. Such machines may be operated in a group to make individual bags finished from the tubing 13 of the roll 10 as fast as the bags are desired for use. Thus, the machine A or a group of these machines may be positioned at the point where it is desired to fill the same with any commodities, and thus, the operator is supplied with any number of bags desired as fast as they are needed and delivered individually so that they can be quickly filled with any product that 30 is desired to be placed in the bags B.

The prefabricated tubing 13 which makes up the roll 10 may be printed upon as indicated by the rectangular portion 32 indicated in Figures 2 and 3. When the material 13 is printed at 32 on the surface thereof either on 40 one side of the material or both sides, it is desirable that the cutting off point 21 and the sealing 19' be properly positioned so that the finished bags B will have the printing 32 in the desired position on the wall of the finished bag. This is regulated by the spacing of the holes 14 in the proper position so that the sealing and cutting off of the tubing material 13 will be at the correct predetermined point. Thus, it is important that the timing of the cutting off knife 18 and the sealing member 19 be such as to operate at the correct moment 45 to make a finished bag B with the printing surface 32 correctly displayed on the side of the bag.

It will be apparent that the electric contact fingers 20 may be substituted by an electric eye 35. The purpose of the fingers 20 or an electric eye 35 which obviously could be substituted for the fingers is to close an electric circuit and operating means to operate the cut off knife 18 and simultaneously operate the sealing member 19 into and out of contact with the tubular material 13. It will be apparent that either the contact 55 electric fingers 20 or the electric eye 35 when the same is substituted therefor may be adjusted into a position whereby bags of different lengths may be completed in the apparatus A.

In Figure 4, we have illustrated diagrammatically a 60 perforating means for the tubular material coming from the roll 10. The tubular material on the roll 10 in Figure 4 is not perforated like that shown in Figure 2, and therefore we provide a perforating means 33 which is positioned between the feed rollers 15 and the electric fingers 20. Thus in this form the tubular material 13 is perforated after it comes from the feed roll 10 to provide the openings 14 and then the material passes under the electric fingers 20 and the bags are finished in the same manner as heretofore set forth and described in Figure 1.

In Figure 5, we have illustrated diagrammatically printing means 34 which prints a mark on the tubing so that when the tubing 13 passes under the electric eye 35, the mechanism for sealing and cutting off the bags heretofore described is operated. In the method of making the bags shown in Figure 5 the electric finger 20 is not used and the operating mechanism for cutting off the bags and sealing the same as illustrated in Figure 1 is caused to be operated by the electric eye 35.

We claim:

1. In apparatus for making bags from a continuous web of thermoplastic material having spaced holes therein, the combination comprising a supporting frame, means on one end of said frame for mounting a supply roll of the material, a pair of feed rolls positioned on said frame adjacent said supply roll, a pair of carrying rolls positioned on said frame longitudinally from said feed rolls, said feed rolls and carrying rolls adapted to move said web along said frame over a table having an electric conductor surface thereon and secured to said frame intermediate said feed and carrying rolls, slender metallic finger means attached to the table for sensing the holes in the material as it passes over the table, said finger means positioned in registry with the spaced holes of said web and adapted to yieldably engage the top surface of the web as it moves along the table and to close an electric control circuit when a hole of the web allows said finger to pass therethrough and contact the electric conductor surface of the table, means adjacent said carrying rolls for transversely cutting the web of material, means adjacent said cutting means for transversely sealing the web of material, means responsive to an electric control circuit closed by said metallic fingers for controlling the timing of said cutting and sealing means to thereby make bags of a length corresponding to the distance between the spaced holes in the material, a pair of discharge rolls positioned at the end of said frame remote from said supply roll, electromechanical means positioned between said sealing means and said discharge rolls for intermittently energizing said feed rolls, carrying rolls and discharge rolls and a tray for receiving finished bags.

2. A machine for making bags from tubular thermoplastic material comprising a horizontal frame, means for supporting a supply roll of the material positioned at one end of said frame, a first pair of feed rolls positioned on said frame adjacent said supporting means, a second pair of feed rolls positioned on said frame in longitudinally spaced relation from said first pair of rolls, said first and second feed rolls adapted to move the material along said frame, means for perforating the material as it passes along said frame positioned between said first and second feed rolls, means for electrically sensing the perforations in the material as it passes along said frame, said sensing means being adjustably positioned on said frame between said perforating means and said second feed rolls, and consisting of contact fingers biased in yieldable contact with the stock and adapted to energize an electric control circuit when said contact fingers pass through the perforations in the stock, means for transversely cutting and sealing the material after it passes through said second pair of feed rolls, said transverse cutting and sealing means being actuated by said sensing means in response to the perforations made in said material, a pair of discharge rolls and tray means attached to the end of said frame opposite said supporting means for respectively discharging and receiving finished bags.

3. The device of claim 2 wherein the electrical sensing means consists of contact fingers biased in yieldable contact with the stock and adapted to energize an electric

control circuit when said fingers pass through the perforations in said material.

4. An apparatus for making bags from thermoplastic tubular material comprising a longitudinally positioned table, the upper face thereof having an electrical conductive surface positioned thereon, perforating means positioned at one end of said table for perforating the material at spaced intervals corresponding to the length of the bags to be made, a plurality of roller means for moving the material through said perforating means and over the electric conductive surface of said table, electrically actuated cutting and sealing means positioned adjacent each other at the end of said table opposite said perforating means to transversely cut and seal the material simultaneously, an adjustable electric sensing device positioned above the electric conductive surface of said table and connected by an electric circuit to said cutting and sealing means, said sensing device having an electric contact member adapted to pass through the perforations in the material for contacting the conductive surface of said table to close the electric circuit as the perforations in the material pass under said sensing device, whereby said sealing and cutting means are actuated by the circuit at fixed intervals corresponding to the passing of the perforations in the material under said sensing device.

5. In apparatus for making bags from a continuous web of thermoplastic material having spaced holes therein, the combination comprising a supporting frame, means on one end of said frame for mounting a supply roll of the material, a pair of feed rolls positioned on said frame adjacent said supply roll, a pair of carrying rolls positioned on said frame longitudinally from said feed rolls, said feed rolls and carrying rolls adapted to move said web along said frame over a table having an electric conductor surface thereon and secured to said frame intermediate said feed and carrying rolls, slender metallic finger means attached to the table for sensing the holes in the material as it passes over the table, said finger means consisting of a slender metallic finger positioned in registry with the spaced holes of said web and adapted to yieldably engage the top surface of the web as it moves along the table and to close an electric control circuit when a hole of the web allows said finger to pass therethrough and contact the electric conductor surface of the table, means adjacent said carrying rolls for transversely cutting the web of material, means adjacent said cutting means for transversely sealing the web of material, means responsive to the electric control circuit closed by said metallic fingers for controlling the timing of said cutting and sealing means to thereby make bags of a length corresponding to the distance between the spaced holes in the material, a pair of discharge rolls positioned at the end of said frame remote from said supply roll, and electromechanical means positioned between said sealing means and said discharge rolls for intermittently energizing said feed rolls, carrying rolls and discharge rolls.
